ELECTRICAL SWITCH DEVICE

A. Henry Morgan, Norwalk, Walter D. Uhl, Fairfield, and Henry R. Angel, Trumbull, Conn., assignors to Electronic Controls, Inc., Stamford, Conn., a corporation of Maryland

Filed Nov. 14, 1962, Ser. No. 237,625
19 Claims. (Cl. 200—104)

This application is a continuation-in-part of our co-pending application Serial No. 146,499, filed October 20, 1961, now abandoned.

This invention relates to the field of switches and relays. More particularly it relates to an improved multi-contact switch and/or relay and methods of construction thereof.

The term "switch" includes both those devices which are locally operated and commonly referred to as switches and those devices which are remotely operated and commonly referred to as relays.

In many application of switches it is necessary that each separate control be able to handle many separate circuits and that related groups of circuits be able to be controlled simultaneously. In much equipment a complex of circuits is used to provide for the various functions to be performed. Some of these circuits are directly controlled by other circuits or by the happening of some mechanical event within the equipment such as the dwell of cam follower or the like; others must be controllable by human selection. If these circuits were each to be controlled by a separate switch or relay the number of elements required would often be so great that the cost and the space required for mounting would be prohibitive. To avoid this, and also to insure that circuits which must be affected simultaneously are so affected, a single switch or relay should be capable of controlling a great number of such circuits.

So great is the number of circuits to be controlled that the need for switches capable of handling a large number of circuits, and not requiring too much space, has still not been satisfactorily solved. Commercially available switches, whether manually controlled or of the relay type are either excessively large, difficult to operate, unreliable, or otherwise unsatisfactory.

Accordingly, it is an object of this invention to provide an improved multi-contact switch and/or relay.

It is a further object of this invention to provide a multi-contact switch and/or relay having a greater number of contact elements in a smaller space than previously possible.

The invention in its more comprehensive aspects provides a very simple and dependable multiple-switch or gang-switch unit and in some of its more detailed aspects provides elements of a novel nature which alone or in mutual association contribute to the simplicity and dependability of device.

With the increasing complexity of electrical circuits and controls it has become very important and urgent that there be provided a multiple switch unit which will operate with complete certainty in each and all components over a very long period of service and under most exacting conditions. The present invention provides such a unit and in a form which is extremely simple to manufacture and assemble; which can be assembled with the simplest of tools, a screwdriver being the only tool required in most cases; which from a few standard components can readily be assembled in a great range in the number of unit switches or unit groups of switches in subassembly modules or in a single ultimate assembly device; which provides easy visual inspection of any individual switch unit in the assembly; and which requires

little increase in power needed for operation even if the number of units is greatly increased.

In its simplest aspect the invention provides a blade or leaf-type switch having improved mounting means for the anchorage end of the movable or shiftable blade element and similarly, when needed, for the relatively fixed blade elements. It also provides improved operating means for the movable end of the shiftable blade element, this means being particularly useful when parallel-paired, oppositely-paired and tier-paired switch units are operated.

The objects, features of novelty and advantages of the invention will better be understood from a consideration of some illustrative embodiments, reference being made to the accompanying drawings, in which:

FIG. 1 is a section through the center of a symmetric embodiment of this invention;

FIG. 2 is an exploded view of a portion of the contact assembly shown in FIG. 1;

FIG. 3 is a section along line 3—3 of FIG. 1;

FIG. 4 is a section along line 4—4 of FIG. 1;

FIG. 5 is a side elevation of another embodiment of a multiple-switch device or assembly embodying the invention;

FIG. 6 is an end view of the assembly shown in FIG. 5;

FIG. 7 is an enlarged vertical section taken on the line 7—7 of FIG. 10;

FIG. 8 is a transverse vertical section taken on the line 8—8 of FIG. 7;

FIG. 9 is a transverse vertical section taken on the line 9—9 of FIG. 7;

FIG. 10 is a horizontal section taken on the line 10—10 of FIG. 7;

FIG. 11 is an exploded perspective view of parts of a blade anchorage assembly;

FIG. 12 is a perspective view of a blade cage frame unit;

FIG. 13 is a partial vertical section of a modified form; and

FIG. 14 is a partial vertical section of the form shown in FIG. 13 but at a different location.

Referring now to FIG. 1, a pair of movable contact arms or blades 10 are shown, though many more may be provided (cf. FIG. 3). One end of each arm 10 is held by a post or sleeve 11 in a manner more clearly shown in FIG. 2. The other end of arm 10 lies in a slot 12 formed in a member 13. Member 13 is disposed transversely, specifically at right angles, to arms 10. Arms 10 have a contact portion 14 thereon. In the rest position of the switch, portion 14 may be in contact with a contact point 15 on a blade or arm member 16 and, as will be seen, when the switch is actuated, portion 14 is moved into contact with a contact point 17 on a blade or arm member 18. Either or both of members 16 or 18 may be connected to circuits to be controlled and are separated from each other and arm 10 by insulating spacers 20a and 20b. As will be seen from FIG. 2, spacers 20a and 20b not only insulate arms 10 and members 16 and 18 from each other, but also function to secure them in place.

Slotted member 13 has a hole formed through it, in its center, through which shaft or plunger 21 passes. A collar 21a on shaft 21 forces member 13 down when upper plunger 22 forces shaft 21 down.

Shaft 21 may be directly controlled by manually operated upper plunger 22 or, as in the embodiment shown, shaft 21 can be controlled by plunger 22 through intermediate members indicated within bracket 26. Plunger 22 is normally maintained in an elevated position by spring 23 and is moved against the force of that spring by the manual operation of plunger 22. Member 13 is restored by a spring indicated at 36 in FIG. 4.

An electromagnet, indicated at 24, may be provided, which can be energized through a circuit completed by one of contact arms 10, to retain shaft 21 in a depressed position after it had been depressed by the manual actuation of plunger 22, or which permits the unit to be used as a relay, the electromagnet itself actuating shaft 21. If such arrangement is included, then of course, some method of breaking the holding circuit energizing electromagnet 24 must be provided.

Also, if desired, provision may be made to indicate when the switch or relay is "made," i.e., when contact portions 14 have moved from points 15 to points 17. As shown, this may be a lamp 25 mounted beneath plunger 22 which plunger would have a translucent or transparent top portion. Lamp 25 may be connected through an appropriate circuit either through the same contact arm 10 as electromagnet 24 or through a contact portion on another of arms 10.

In operation plunger 22 may be manually depressed against the pressure of spring 23. Plunger 22 in turn depresses shaft 21 through intermediate members and with it slotted member 13. When member 13 moves down it pivots arm 10 about its fixed point at sleeve 11, moving contact portion 14 from contact point 15 to contact point 17. In this embodiment this might complete a circuit energizing electromagnet 24 and lamp 25. Such a circuit would be conventional in itself and illustration is not deemed necessary.

It will now be understood that no matter how many arms 10 are used, each is directly and positively moved through the motion imparted to slotted member 13. Location of contact portions 14 near slotted bar 13 increases the positive nature of this transfer of force.

Referring now to FIG. 2, a particular embodiment of the contact assembly portion of the switch and/or relay is shown. A blade member 30 has a pair of notches 31 formed therein. These notches are shaped so that opposite notches on adjacent arms define an aperture substantially the shape of sleeves 11. In the illustrated embodiment, sleeves 11 are cylindrical and each notch 31 preferably is defined by an arc having substantially the same radius of curvature as posts 11 and a length less than half the circumference of posts 11, thereby insuring that adjacent ones of member 30 do not touch when positioned about sleeves 11.

Member 32, a lead connection blade, illustrates one way of providing external connections from the switch assembly. Member 32 is also provided with notches 31 in a manner identical to those of member 30 and these two members, 30 and 32, are placed one on top of the other, between spacer bars 20a and 20b, positioned adjacent to apertures 33 so that sleeves 11, when inserted through the apertures, will cooperate with the notches to hold the members securely in position. Members 30 and 32, together, may be considered to comprise arm 10, FIG. 1, or member 30 alone could be that arm. Similarly, members 30 and 32, together, could be members 16 or 18 as well, since all of these are essentially the same in the portion illustrated in FIG. 2.

It will be appreciated that only a portion of the contact assembly is illustrated in FIG. 2. If members 30 and 32 are considered to constitute arm 10 sandwiched between spacers 20a and 20b, then a pair of members 16 and 18 have been omitted to avoid obscuring pertinent details of the construction. It should be appreciated that, as a result of the provision of notches 31 which cooperate with sleeves 11, and spacers 20a and 20b, a rigid mounting is obtained without need for conventional methods of fastening, such as screws through the various members.

Top piece 34 cooperates with spacer 20a to hold member 16 in position, and bottom piece 35 similarly cooperates with spacer 20b to hold member 18 in position. It should be understood that arm 10 or members 16 and 18 could be constructed of one piece instead of the two shown, through the embodiment illustrated in FIG. 2

permits a choice of external connections to be offered. The entire contact assembly may be held together by several fasteners which can be inserted through sleeves 11 and passing through appropriate apertures in switch housing (FIG. 1) and which is indicated at 27 and 28 of FIG. 1.

The contact assembly illustrated in FIGS. 2, 3 and 4, may, in turn, be stacked simply by extending shaft 21 any desired length so as to protrude through slotted member 13 and by providing an aperture in bottom piece 35 so that shaft 21 can cooperate with other slotted members.

FIG. 3 shows more clearly the appearance of the contact assembly with the topmost members 16 arranged side by side, and in the embodiment illustrated each contact assembly has twelve sets of contacts.

FIG. 4 illustrates a detail of the assembly of the switch or relay; the return spring which is indicated at 36 and which can be of any configuration such that it opposes the downward travel of slotted member 13 and shaft 21 and restores member 13 to its rest positions when the operating force, e.g., depression of plunger 22 is removed.

When used as a relay, of course, the plunger portion of the assembly shown in FIG. 1 could be eliminated and the unit would be operated solely by the electromagnet indicated at 24.

FIG. 5 shows a multiple-switch device or assembly 40 which comprises a stack of substantially identical multiple-switch units, modules or "wafers" 41 and a single manual operator or pushbutton 42, the units being secured together by a top plate 43 and a plurality of screws 44. The length of the screws is selected according to the number of tier, module or wafer units 41 which are assembled in the stacked composite unit or complete switch assembly device.

It has been found to be extremely helpful for inspection to form all panels of a non-breakable transparent insulating material, such for example as "Lucite," "Plexiglas," "Lexan" or the like, but no attempt has been made to show the material as being transparent because of the confusion which would be caused by showing in simple views all parts which could be seen. "Lexan," a polycarbonate plastic, is at present preferred because of its high temperature resistance, dimensional stability, moisture resistance and other characteristics which are favorable for the preferred use. Obviously, many other plastics are suitable for the application.

Each unit, module or wafer 41 comprises a housing which includes a bottom wall 47, a top wall 48, side walls 49 which may be interfitted by tongue and groove in the top and bottom walls so as to be removable by end sliding movement, and end walls 50 which, as shown in FIG. 11, comprise transverse spacer bars 51 and vertical spacers 52 which may be made integrally with the transverse bars if desired. The vertical spacers 52 are mated with recesses 53 which provide variable spacing for clamping a plurality of switch blades or plates 54 of the flexible leaf type. The blades are provided on the sides with arcuate recesses or notches 55 which embrace the sides of the vertical spacers 52 whereby the blades are held firmly in position between the two transverse spacer bars 51. The spacer bars constitute anchorage means for the outer ends of the switch blades, the lower one being referred to as the base member and the upper one as the clamp member. All housing parts are of insulating material, preferably a clear plastic, as stated.

At least some of the vertical spacers 52 are provided with apertures 56; and the transverse spacer bars 51, and the top and bottom walls of the housing are provided with aligned corresponding apertures for the screws 44 which hold the assembled wafer units together and to the top plate 43. Preferably each wafer unit has its parts secured together to form a self-contained independent unit before it is secured in an assembly with other parts as here shown by tubular rivets 45.

As shown, there are three superposed rows of switch blades 54 anchored in each end of each wafer or stack unit housing, all secured in the end wall anchorages in the same way but some having different functions from others. The upper row 54a and the lower row 54c of switch blades are substantially fixed, although all the switch blades here are springy or resilient and have some movement in operation; and the blades of the middle row 54b are shiftable to move to cooperative positions relative to the upper and lower rows. All switch blades are provided with contacts 57 and it will be understood that the outer ends of the blades which are exposed beyond the end wall of the housing have suitable electrical conductor leads secured to them. As here shown, the outer end portions 54d are made as separate parts with notches like the main part of the blade. There are a number of advantages in making the switch and terminal blade elements of separate parts. One, which has already been mentioned, is that it provides a choice of types of terminal connections at the outside. Another is that the contact switch portions can be tempered for springiness while leaving the terminal portions soft. If desired, the outer terminal portions and the inner switch portions can be soldered or welded together.

The switch blades of the middle row 54b have inner end extensions 58 by which the blades are actuated along lines transverse to the plane of the blades.

Means are provided for limiting or confining the movements of the switch blades to assure that all contacts of the row on one side of the movable blades are separated before the contacts of the row on the other side are brought together. The means here shown comprises transverse stop bars 60 located near the contacts, here outwardly or outboard of them. Here the bars comprise parts of a unitary cage grid 61 having apertures 62 providing limited movement of the blades. The cage grid 61 is held at its upper and lower ends in grooves 63 formed in the bottom and top walls 47, 48 respectively of the housing.

Means are provided for operating the movable or shiftable middle row switch blades by action on their end extensions 58, the means here shown comprising a transverse operating bar 65 which moves transversely to the planes of the switch blades and is provided with elements which operatively engage the ends of the blades without binding during travel. The bar is here shown as being provided on each side with a slot or groove 66 which receives the ends of all the shiftable blade ends on a side with such allowable end and side movement as may be necessary to avoid binding. The grooves are slightly over-depth and flared at top and bottom for such movement accommodation.

Means are provided for actuating each operating bar 65 for each housing module or wafer unit in a controlled manner, as by guide and preferably anti-tilt arrangements, to assure that all switches of a bank or row are operated at each actuation. As here shown an operating push rod or plunger 70 is rigidly connected to the bars 65 of all wafer units and the plunger is guided, as by a sleeve 71 closely and slidably fitting its upper end. The sleeve 71 is secured in the top plate 43 of the assembly and is provided with suitable fittings, such as nuts 72, for securing the whole switch device or assembly to a suitable support. The plunger 70 is intended to act as a pushbutton for momentary bottom contact (or while held down) and the plunger for this purpose carries a pushbutton finger piece 73 at its upper end.

Preferably when stacks of modules or wafer units are used the plunger 70 is made in segments 74, one for each wafer unit in a stack, and these segments have reduced ends which telescope together at bars 65, as shown in FIG. 7, to embrace the bars and connect them in the plunger line.

When pushbutton actuation is used it is desirable to provide a spring return for the plunger and bar assembly.

This might be provided for the plunger sleeve (as in FIG. 1) but conveniently may be provided by equipping each wafer unit with a spring 75 under each end of the bar, the springs preferably being seated at the ends in recesses 5 in the bar and bottom wall of the housing.

Apertures 76 are provided in the top and bottom walls of the housings (except the bottom wall of the lowest housing where it is not needed) for the passage of the plunger 70. The apertures are shown as being oversize but may fit closely, if desired, for better guidance and more complete dust exclusion. The plunger 70 is retained against excess outward movement in the sleeve 71 by any suitable means, as here shown by a rubber O-ring or spring ring 77 carried in a groove of the plunger which aids also in excluding dust.

The grooved bar 65 provides operation of the switch blades in both directions under positive movement and at the same time allows relatively free movement with very little friction between the bar and the switch blades, 20 the flared shape of the grooves allowing the blades to assume various inclined positions without binding. If the blades were clamped rigidly there would be considerable bending stresses with the possibility of crystallization and breakage.

25 The straight bar with grooves can also be readily moved in by endwise travel from one side of the pre-assembled unit and slid over the ends of the switch blades. Then the plunger segments are assembled with the bars and the main plunger and the wafers or modules secured together 30 in the full assembly. The side plates 49 are removable by endwise movement to open the housing on the side and permit the bars to be inserted and removed. The side plates 49 have small projections 49a which engage the inner edges of the stacked spacers 51 to hold the plates 35 in closed position. There is sufficient spring in the plates to permit them to be moved in and out.

When it is desired to clean the switch contacts the side plates 49 can be quickly removed for access. The wafer housing is practically fully sealed against dust but there 40 may be some corrosion over a long period of time and there may be a slight accumulation of dust. If desired, the bars 65 may also be removed, the plunger elements first being taken out.

The present arrangement is very convenient in the 45 manufacture, sale and eventual use of the switch units. The wafer units or modules 41 can be assembled with all the switch blades and terminal blades clamped in place between the spacer bars and the whole assembly secured together by the tubular rivets 45. The side closure members 49 keep out dust and corrosion in storage. The operating bars 65 and their springs 75 may be inserted in the original assembly or may be inserted at a later time when stacks of wafer units (or one unit if so desired) are set up with the operating means—pushbutton, relay or 50 the like—and mounted for use. The plunger segment elements 74 are preferably added in final assembly.

The form of wafer blade anchorage means shown in 55 FIGS. 13 and 14 is much like that of the form shown in FIGS. 1 to 4 in that spacer sleeves 11' are provided for engagement by the side notches of the switch blades 10' and the terminal blades 32' and that the transverse spacer bars 20' are provided with holes to fit over the sleeves. At the ends of the spacers 20' there are semi-circular vertical spacer elements for the outer notches of the last 60 blades in a row where a full sleeve cannot economically be used. Such side spacers 52a are shown in the other form illustrated in FIGS. 10 and 11.

The spacer sleeves 11' and spacer elements may be formed integrally with the plate 48' or may be made as 65 separate members which are inserted in holes in the plate. When formed integrally, there is preferably an annular depression 11b around the bottom end of the spacers to avoid fillets to interfere with the blade positioning notches.

Rivets 45' secure the parts of the pre-assembled wafer 70 units together; and screws 44' secure wafer units together

and to an anchorage part, such as a top plate 43'. The bottom spacer 20' is notched into the bottom wall plate 47'.

When the spacer sleeve is carried by an upper plate 48' the parts are turned upside down so the blades 10' and 32' and the spacers 20' can be dropped down on the vertical spacer elements 11' and the coordinating side projections (like 52a of the other form) during assembly.

It is thus seen that the invention provides improved switch mounting means, improved switch operating means, improved switch modules and improved switch housing means.

While certain embodiments of the invention have been illustrated and described by way of example, it is to be understood that there may be various other embodiments and modifications within the general scope of the invention.

We claim:

1. A switch comprising

a housing,

a plurality of essentially parallel resilient, switch contact support blades side-by-side within and supported by the housing and extending through the wall and into the housing in essentially coplanar relationship at one end of the housing so that they are electrically insulated from one another,

a rigid insulator actuator bar within the housing transverse to the blades within the general plane of the blades and having slot means receiving the other unsupported ends of the blades and movable out of the common plane of the blades to deflect the movable contacts, and

a plurality of fixed contacts opposed to individual contacts on the blades so that movement of the blades by the actuator will cause the movable contacts to move in unison between open and closed position with their opposed fixed contacts, said housing closely enclosing the switch contacts, blades and actuator bar.

2. The switch of claim 1 in which the actuator bar is generally perpendicular to the blades and mechanically confined so that the ends of the blades cannot escape from the slot means.

3. The switch of claim 1, in which the slot means of the actuator is a continuous slot so that the bar may be slid in the direction of the slot to receive the ends of all blades extending toward it from one side, said slot being tapered to diverge outwardly in order to permit flexing of the blades without binding.

4. The switch of claim 2 in which two essentially coplanar groups of switch contact support blades extend toward the actuator bar from opposite sides and are received in slots on opposite sides thereof.

5. The switch of claim 4 in which the housing is generally rectangular in shape and thin in the direction of the movement of the contacts and the actuator bar relative to its width and length, the thickness being determined by the spacing between contact pairs.

6. The switch of claim 5 in which the fixed contacts are supported on blades generally parallel and opposed to the blades supporting the opposed movable contacts so that the respective blades lie generally in planes defined by the blades which are parallel and close spaced to one another.

7. The switch of claim 6 in which the housing is formed by stacking alternately insulator strips transverse to the blades and the blades in a plane and coupling said stacks together to define the end walls between top and bottom walls so that the individual blades extend through the end walls to provide terminals for their respectively supported contacts.

8. The switch of claim 7 in which side walls of the housing are formed by strips which slide in place between

grooves in the top and bottom walls in their edges which extend laterally beyond the end walls.

9. The switch of claim 6 in which two sets of fixed contacts are supported on blades generally parallel and opposed to opposite sides of the blades supporting movable switch contacts opposite each of the respective fixed contacts so that the respective blades lie generally in three generally parallel close spaced planes.

10. The switch of claim 9 in which switch contacts are located closer to the actuator member than to the supported ends of their supporting blades and in which lateral insulating elements are located between the fixed and the movable contact supporting blades such that the fixed contact supporting blades are limited in their ability to follow the movable blades as they are moved by the actuator bar away from the fixed bar.

11. The switch of claim 10 in which the lateral insulating elements are part of a grid also having elements extending between the switch blades and having its edges received in grooves in the top and bottom walls of the housing.

12. The switch of claim 5 in which access to the actuator bar is provided by an opening in the housing which permits entry and access to the actuator bar of drive means generally perpendicular to the bar.

13. The switch of claim 12 in which the drive means is a manual push-button fixed to the housing and having means extending into the housing and into contact with the actuator bar to move said bar.

14. The switch of claim 12 in which the drive means is electromagnetic means fixed to the housing and having means extending into the housing and into contact with the actuator bar to move said bar.

15. The switch of claim 12 in which the actuator bar is biased into one position to which it will return if released and the drive means moves it to another position against said bias force.

16. The switch of claim 5 in which the bias force is provided by the resilience of the movable switch contact supporting blades.

17. The switch of claim 15 in which the bias force is provided by auxiliary spring means acting against the actuator bar.

18. A switch assembly in accordance with claim 12 in which a plurality of similar switches having their housings fixed together with top and bottom walls adjacent and actuator members are arranged parallel and aligned with a common drive member and in which rigid connection segments extend between and into contact with each of the actuator bars in adjacent switch housings passing through aligned openings in the top and bottom housing walls.

19. The switch assembly of claim 18 in which drive means is affixed to the switch assembly and provides drive means essentially perpendicular to an actuator bar at the top of the assembly through an opening in its housing and auxiliary spring means is provided between the actuator bar most remote from the drive means and its housing.
